Des. 239,986
Patented May 25, 1976

239,986

BELT-ATTACHABLE CARRYING CASE

Kenneth W. Artz, Albuquerque, N. Mex., assignor to Koszegi Leather & Vinyl Products, Inc., South Bend, Ind.

Filed Dec. 11, 1974, Ser. No. 531,488

Term of patent 14 years

Int. Cl. D2—07

U.S. Cl. D2—400

Fig. 1

Fig. 2

Fig. 3

FIG. 1 is a right rear perspective view of a belt-attachable carrying case showing my new design;

FIG. 2 is a left side elevational view thereof; and

FIG. 3 is a rear elevational view thereof, the front elevation being flat, plain and unornamented.

I claim:

The ornamental design for a belt-attachable carrying case, as shown and described.
